UNITED STATES PATENT OFFICE.

TIMOTHY SULLIVAN, OF FALL RIVER, ASSIGNOR TO THE DUTCHER TEMPLE COMPANY, OF HOPEDALE, MASSACHUSETTS.

LOOM-TEMPLE.

SPECIFICATION forming part of Letters Patent No. 416,692, dated December 3, 1889.

Application filed July 9, 1888. Serial No. 279,436. (No model.)

To all whom it may concern:

Be it known that I, TIMOTHY SULLIVAN, of Fall River, county of Bristol, State of Massachusetts, have invented an Improvement in Loom-Temples, of which the following description, in connection with the accompanying drawings, is a specification, like letters on the drawings representing like parts.

It is of especial advantage in looms to have the temple-stand and its holding devices take up the least possible space on the breast-beam in the direction of the width of the loom, for the less the space taken up by the stand the wider may be the reed and the cloth which may be woven thereon without touching any part of the stand.

Prior to my invention it has been customary to provide the temple-stand with a web or flange located at one side the shank of the temple, the said web being slotted for the reception of two screws, by which to attach the stand to the stand-plate, it in turn being slotted to be attached to the breast-beam.

In accordance with my invention the slotted web or flange at the side of the stand has been dispensed with, and the stand-plate co-operating with it has been provided at and near its outer end with a raised shelf recessed to form two lips or ribs, between which is left a groove for the reception of the narrow foot of the temple-stand. The screws to attach the foot of the stand to the stand-plate are extended upwardly through the shelf from below and enter threaded holes in the foot of the stand below the shank of the temple, as will be described.

By dispensing with the web or flange on the stand the selvage of the cloth may travel close to the temple-stand, and yet in the movement of the cloth not travel horizontally above or rub against any part of the said stand.

The invention consists, essentially, in the combination, with a temple-stand having a narrow foot, of a stand-plate recessed for the reception of the said foot, and bolts or screws extended through the said plate directly into the foot of the stand below the temple-shank, as will be described.

Figure 1 in top or plan view shows a loom-temple embodying my invention and its stand-

plate, the latter being secured to the breast-beam, only a portion of the latter being shown; Fig. 2, a section of Fig. 1 in the dotted line x ; and Fig. 3 is a top or plan view of a loom-temple of usual construction, upon which this my present invention is an improvement.

The trough a , cap or cover b , roller b^x , shank b' , and spring b^2 are and may be all as usual in loom-temples. Ordinarily the temple-stand c has at its inner side a rib or flange c' , (see Fig. 3,) slotted, as at c^2 , to receive holding-screws 2 , by which to confine the stand to the stand-plate d , it in turn being slotted, as at d^2 , to receive a fastening-bolt 3 , which enters a corresponding slot in the breast-beam A , the bolt having applied to it a nut 16 .

Wishing to narrow the temple-stand as much as possible, so as to leave a space as wide as possible for the cloth at the top of the breast-beam, so that the selvage of the cloth will not in its movements travel over any portion of the stand, I have dispensed with the usual web or flange c' , extending laterally from the temple-stand and over the top of the breast-beam, and have made the foot of the stand as a narrow bar f , connecting the two bearings $f' f^2$ for the shank b' , the said foot entering the recess formed between the ribs or lips $5 6$ on the elevated shelf or stand-plate d , slotted at d^2 and secured by a screw or bolt 3 to the breast-beam A .

In Fig. 1 the dotted line $y y$ is supposed to represent the selvage of the cloth being woven, and it will be noticed that it may rest on the breast-beam from its inner to its outer side, and in passing over the same not touch any part of the temple-stand, whereas by referring to Fig. 3 it will be seen that were a like line $y y$ put thereon from the same part of the trough it would cross the web c' .

In practice with the old form of stand in Fig. 3 the selvage cannot come closer to the temple than the line $y' y'$.

The breast-beam herein shown is supposed to be of metal flanged at its upper side to leave a space for the reception of the plate d .

I claim—

The temple-stand having a narrow foot f , combined with the stand-plate, recessed, as

described, for the reception of the said foot, and with screws extended within said recess through the said stand-plate into and to rigidly connect the said foot and stand-plate 5 vertically below the bar b' of the temple, and whereby the breast-beam outside the bearings for the bar b' is left unobstructed for the passage of the cloth, substantially as described.

In testimony whereof I have signed my name to this specification in the presence of two subscribing witnesses.

TIMOTHY SULLIVAN.
